UNITED STATES PATENT OFFICE.

ALVIN W. PUFFER, OF MEDFORD, MASSACHUSETTS, ASSIGNOR TO THE PUFFER MANUFACTURING COMPANY, A CORPORATION OF MAINE.

JAR-HOLDER.

SPECIFICATION forming part of Letters Patent No. 690,077, dated December 31, 1901.

Application filed July 19, 1901. Serial No. 68,873. (No model.)

To all whom it may concern:

Be it known that I, ALVIN W. PUFFER, of Medford, county of Middlesex, and State of Massachusetts, have invented an Improvement in Jar-Holders, of which the following description, in connection with the accompanying drawings, is a specification, like letters on the drawings representing like parts.

The present invention relates to soda-fountain apparatus and is embodied in a syrup-jar holder of that class in which the jar is supported in a frame which is adapted to be moved into and out of a suitable space in the main casing of the fountain, the frame being movable outward to remove the jar for cleaning or other purposes and movable inward to inclose the jar within the casing.

The object of the invention is to obtain a jar frame or support which is capable of being easily manipulated, the said frame in accordance with the invention being hung on supports pivotally connected above the jar, the said supports bearing the weight of the frame and jar as the same are moved outward or inward.

In accordance with the invention the frame into which the jar is fitted is pivotally connected at or near its lower end with pivotally-supported hangers, the pivotal connections allowing the frame to be swung outward on the hangers and to be tipped forward when swung outward, so as to clear the top of the jar from the recess within which it is normally inclosed, so that the said jar can be removed from the frame. The tipping of the frame is limited by means of links or connecting device having a sliding connection between the frame and the supporting members, or "hangers," as they may be called, the said links being arranged to support the frame and prevent further movement thereof after it has been tipped forward far enough to permit the removal of the jar. The frame is provided with the usual inclosing plate, which supports the syrup faucet and pipe and closes the recess in which the jar is contained, and the frame is arranged to be held in position when moved inward by means of a suitable fastening device, such as a latching projection, from which it is disengaged by a slight upward movement, being then swung out-

ward without sliding contact with any part of the main frame or casing.

Figure 1 is a vertical section through a soda-fountain, the line of section being taken through the recess which holds the syrup-jar, the jar and its supporting-frame being shown in elevation. Fig. 2 is a similar view of a portion of the apparatus, showing the syrup-jar frame in position for the removal of the syrup-jar; and Figs. 3 and 4 are details on a larger scale, showing the means for retaining the frame in position.

The jar A, which may be of any suitable or usual construction, being usually a rectangular porcelain jar, is supported in a frame consisting of two supporting members or hangers a, pivotally connected at their lower ends with a bottom plate a², to which are connected front and rear members a³ and a⁴, the former constituting an inclosing plate for the recess in which the syrup-jar is contained and also a support for the faucet b and pipe b², through which the syrup is drawn. The jar is supported at the bottom by the coupling member b³ of the pipe b², which may be of the usual construction and is held in the frame by means of a lateral supporting member or band a⁵, extending from the front plate a³ to the rear member a⁴. In accordance with the invention the hangers a are provided with a cross member a⁶, pivotally connected with a suitable support c near the top of the casing, and when the jar is in its normal position, as shown in Fig. 1, the supporting-frame rests near its front end upon the bottom member or floor d of the chamber in which the jar is contained. The hangers a also contribute to the support of the jar A, the center of gravity of which is behind the point of contact with the member d, and the jar and frame are prevented from swinging forward by means of a retaining-shoulder d², which fits in a notch a⁷, (shown as behind the front plate a³,) the said projection and notch being so shaped that when the frame is pushed into position it will slip over and lock automatically.

To remove the jar, the front member a³ may be lifted far enough to clear the projection d², and the said frame will then be supported upon the hangers a and may be swung forward to the position shown in Fig. 2, the

parts being so arranged, as shown, that force of gravity will tend to swing the jar and frame forward without effort on the part of the manipulator. The lower member of the frame 5 is inclined upward toward the rear, so as to clear the floor d while the frame is being swung, the hangers thus constituting the sole support.

In order that the top of the jar may be carried clear of the main casing without bodily moving the frame or jar to any great extent, the member a^2 of the frame is pivotally connected at a^3 with the hangers a , so that as the frame moves forward it is free to tip with relation to the hangers, as indicated in Fig. 2.

In order to limit the tipping movement of the frame to the desired extent, the front portion of the frame is connected with the hangers by means of links or connecting members e , 20 which are shown as pivotally connected at e^2 with the frame near the lower front end thereof, extending from the said frame to the hangers, where they are adapted to be engaged at the end of a predetermined movement by 25 studs e^3 , the links e being shown as provided with elongated slots e^4 , adapted to slide along the said studs until engaged thereby at the ends of the slots.

In order that the frame as a whole may 30 be easily removed, if desired, the supporting member a^6 may be slipped over into the throat of the hook or support c , as best shown in Figs. 3 and 4, and to prevent the said cross member a^6 from being accidentally lifted from 35 its seat in the hook the support is provided above the hook with a retaining-screw c^2 , the head of which is covered by the front plate a^3 when the syrup-jar A is closed in.

By the construction above described it is 40 obvious that the jars can be easily removed or replaced, the frame swinging forward without sliding contact in response to a slight upward movement of the front plate a^3 , while the frame as a whole can be removed by 45 merely unhooking the cross member a^6 from the support c , the retaining-screw c^2 , if used, having been previously removed.

I claim—

1. The combination with the recess for the 50 jar; of the jar-frame; hangers for said frame pivotally connected thereto and pivotally sup-

ported in the recess above the frame and near the front of said recess whereby the said frame tends to swing forward out of the recess and to tip forward with relation to the hangers by 55 force of gravity; means for retaining said frame in the recess; and means for limiting the tipping movement thereof relative to the hangers.

2. The combination with a frame or support 60 for a syrup-jar; of supporting-hangers pivotally connected with said frame and pivotally supported above and at one side of the center of gravity thereof; and means for limiting the pivotal movement of said frame with re- 65 lation to said hangers, as set forth.

3. The combination with a frame or support for a syrup-jar; of hangers pivotally connected with said frame and adapted to support said frame when swung forward; a pivotal 70 support for said hangers above the point of connection with the frame; and a link connecting the front of the said frame with one of said hangers said link having a sliding connection with one of said parts, substantially 75 as described.

4. The combination with a chamber for the syrup-jar; of a hook-shaped support near the top of said chamber; a hanger pivotally suspended in said hook-shaped support; a frame 80 for the syrup-jar, comprising front, rear and lower members, the said lower members being pivotally connected with said hangers; and means for connecting the said lower members with the lower wall or floor of the chamber 85 to maintain the frame in position, as set forth.

5. The combination with the hook-shaped support c ; of the hangers a and cross member a^6 ; the retaining-screw c^2 , the support for 90 the jar with which the said hangers are pivotally connected; the link e connecting a portion of said support with said hanger; and means for retaining the said support with the jar in vertical position as set forth. 95

In testimony whereof I have signed my name to this specification in the presence of two subscribing witnesses.

ALVIN W. PUFFER.
